AMMUNITION BELT LINK GUIDE MECH-
ANISM FOR AUTOMATIC GUNS

Edward Cyril Holton, Los Angeles, Calif.

Application April 9, 1945, Serial No. 587,258

19 Claims. (Cl. 89—33)

1

My invention relates to automatic guns and, more particularly, to an improved cartridge-guiding mechanism therefor. It is particularly useful in connection with Browning-type guns and will be exemplified as applied thereto, though it should be understood that it can be adapted, with slight modifications, to other automatic guns.

The ammunition belt fed to automatic guns usually comprises a plurality of cartridges suitably connected together, modern practice involving the use of a disintegrating-type belt in which the cartridges are connected by metallic links. The linked ammunition is advanced step by step along a transverse feedway by a suitable pawl mechanism. The foremost cartridge is moved into an extraction position upon contact with the usual cartridge stops preparatory to extraction from the belt and insertion into the gun barrel.

The cartridge is extracted from the link by an extractor which cams over the rear end of the cartridge and engages the groove or cannelure of the cartridge case. Through this engagement, the extractor draws the cartridge from the belt and moves its rim downward into the T-slot in the forward face of the breech bolt. This occurs during recoil-induced rearward movement of the breech bolt. During subsequent forward movement of the bolt, the cartridge is forced into the barrel, with which it is now aligned, the barrel being below the level of the feedway. Also during this forward movement of the bolt, the next or following cartridge of the belt is advanced into extraction position. During such advancement, it is desirable that the link that held the previously extracted cartridge be used for the proper placing of the following cartridge in correct position for extraction.

It is an object of the present invention to provide a novel structure for guiding, in a positive manner, the links employed in an ammunition belt during and after extraction of the cartridges from the links by the gun-feeding mechanism. Extraction of each cartridge from the belt frees a link, and the present invention provides a positive guide therefor to prevent misalignment and binding, such as frequently occurs, particularly if the link is permitted to move forward upon release. Such forward movement is prone to take place, particularly if the muzzle of the gun is depressed, as must often be the case when the gun is mounted in an airplane wing or in a turret.

It is an object of the present invention to provide a link-guiding mechanism employing a plunger which advances inwardly opposite a link during or immediately after its release to retain

the link in proper alignment and prevent binding, which might result in stoppage of the gun. This plunger acts in the nature of a movable gate bounding a link-receiving passage, and it is an object of the present invention to provide a movable member, actuated automatically by the operation of the gun, to form one boundary of a link-receiving passage. It is a further object of the invention to provide such a movable plunger which assists in maintaining proper alignment of the ammunition belt during feeding along the feedway. In this connection, the aligning of a forward or leading portion of each link, while the rear or trailing portion of the link is still attached to the next cartridge, serves to guide the entire movement of the ammunition belt and results in improved performance and firing characteristics of the gun.

The presence in the belt of a short round will often jam or stop the gun. This may result in a very serious situation, particularly if the gun is positioned remote from the gunner, e. g., in the wing of an airplane, as it is then impossible to extract manually the faulty cartridge or round and resume firing. A short round is the result of a decrease in overall dimension of the cartridge and may result from defective manufacture or accidental inward displacement of the bullet in the case during handling of the ammunition. In some instances, the round may be shortened in the feedway if the bolt strikes the rear of the cartridge or when the extractor cams upward over the rear of the cartridge case. In the usual automatic gun, the nose of each bullet slides along, or immediately adjacent, a front wall of the feedway. Forward pressure applied to the rear of the cartridge case may thus be sufficient to force the bullet farther into the case, particularly if the forward end of the case is split or improperly crimped on the bullet, thus resulting in a short round. A short round will jam or stop the gun if the cannelure of the cartridge is disposed beyond the reach of the extractor.

It is an object of the present invention to maintain the cartridge cases in alignment so that their cannelures are aligned and within reach of the extractor, this being accomplished by proper alignment of the links to prevent the cartridges from moving too far forward in the feedway when contacted by the bolt or extractor. Extensive tests have shown that the present invention will overcome jamming because of the presence of short rounds in the ammunition belt, while at the same time not interfering with the normal opera-

tion of the gun and without decreasing its firing rate.

In conventional automatic guns, the extraction position of the leading cartridge is determined by engagement with front and rear cartridge stops. Also, a link stripper is usually provided to retain the link when the cartridge is being extracted. Conventionally, these cartridge stops and the link stripper are separate units and must be separately withdrawn for inspection or for changing the gun from right-hand operation to left-hand operation, or vice versa. This operation is time consuming and difficult to perform, particularly if it must be accomplished by gloved hands.

It is an object of the present invention to provide a readily removable unitary attachment for an automatic gun, and to which the cartridge stops, the link stripper, and/or a link guide means of the invention are secured, thus facilitating insertion, withdrawal, and shifting of these elements. In this connection, the invention has among its objects the attachment of the cartridge stops, link stripper, and/or a link guide means to a base plate to form a unitary structure which can be quickly inserted for either right-hand or left-hand operation of the gun, thus providing a unitary structure which can be easily handled and which will prevent loss or dropping of small parts when the gun is being changed from right-hand to left-hand operation, or vice versa.

It is another object to removably connect a link-discharge chute to such a unitary structure to facilitate shifting the position of the chute when changing from right-hand to left-hand operation, or vice versa.

Further objects and advantages of the invention will be evident to those skilled in the art from the following description of exemplary embodiments.

Referring to the drawings:

Fig. 1 is a fragmentary top view of a machine gun with cover removed and showing the invention in place;

Fig. 2 is a vertical sectional view, taken along the line 2—2 of Fig. 1, but showing the cover of the gun in partially raised position;

Fig. 3 is a fragmentary side view of the gun, taken as indicated by the arrow 3 of Fig. 1;

Fig. 4 is a section taken along the line 4—4 of Fig. 3, and showing the invention as used for left-hand feed; showing also (by dotted lines) the position of the invention for right-hand feed;

Fig. 5 is a perspective view of the embodiment of the invention shown in Figs. 1 to 4, and indicating its relationships to a cartridge in the extracting position;

Fig. 6 is an elevation of the embodiment shown in Fig. 5;

Figs. 7 and 8 are, respectively, plan and end views, Fig. 7 being partially in section and being taken along the line 7—7 of Fig. 6;

Fig. 9 is a perspective disjoined view of an alternative embodiment of the invention;

Fig. 10 is a rear view of the embodiment of Fig. 9, taken as indicated by the arrow 10; and

Fig. 11 is a fragmentary perspective view of another embodiment of the invention in which the plunger carries a curved link-contacting member.

The complete structure of the machine gun and the operation thereof will not be described in detail as these are readily understood by those skilled in the art. The drawings show only those portions of an exemplified machine gun structure pertinent to the invention.

As shown, the machine gun includes the usual side plates 10, between which is positioned a forwardly-disposed trunnion block 11. The machine gun is provided with the usual hinged cover 12 which, when closed, forms the upper boundary of a transverse feedway 13, along which is automatically advanced an ammunition belt 15 of conventional construction, shown as comprising a plurality of cartridges 16 interconnected by links 17. Each link 17 includes a bifurcated forward or leading portion bent to surround the leading cartridge of each pair to form two loops 18 and 19, respectively providing front and rear faces 20 and 21. Each link also includes a rear or trailing portion bent around the adjacent cartridge to form a loop 22 hinged to this cartridge. The loops 18 and 19 frictionally engage the case of the leading cartridge, this cartridge case being indicated by the numeral 25, the forward loop 18 being frustoconical to engage the usual tapered portion of the case 25. In the forward end of each case 25 is the usual bullet or projectile 26 having a nose 27.

The gun provides a barrel 30 having a rifle bore 31 at an elevation below the feedway 13. Upon recoil, the barrel 30 moves rearward a limited extent and operates the breech mechanism of the gun, including a longitudinally-movable breech bolt 32 which moves rearwardly a greater distance than does the barrel 30.

The ammunition feed mechanism of the gun includes an actuating pawl means 33 carried by the cover 12 and actuated by a lever 34 having a follower riding in selected grooves 35 of the breech bolt 32. The actuating pawl means 33 successively engages the cartridges to advance the belt along the feedway 13, there being an auxiliary pawl means, not shown, for retaining the cartridges against opposite movement.

The leading cartridge of the belt is advanced to an extraction position corresponding to the cartridge A of Fig. 1, which extraction position is determined by the invention, as will be later described. An extractor 36 is carried by an arm 37 pivoted to the breech bolt 32. During forward motion of the breech bolt, the extractor cams upward over the rear end of the cartridge and enters the cannelure 38 thereof. As the breech bolt 32 moves rearward, the extractor withdraws the cartridge from the belt and forces it downward into a T-slot 39 on the forward face of the breech bolt, while at the same time expelling the previous cartridge case. As the breech bolt moves forward, it forces its retained cartridge into the barrel 30 for firing. A new cartridge is moved into the extraction position during the forward movement of the bolt.

On opposite sides of the gun are mounted correspondingly-formed brackets 42 providing a series of spaced lugs 43 traversed by a removable pin 44. Conventionally, the usual stop members and link stripper are individually mounted in the spaces between these lugs, being held in place by the pin 44.

The preferred embodiment of the invention includes a cartridge guide means or a link guide, best shown in Fig. 5 and comprising a unitary guide structure indicated generally by the numeral 50. This unitary guide structure is adapted for right-hand or left-hand gun feed and comprises a base plate 51 with lugs 52 and 53 spaced longitudinally of the gun axis to be disposed between pairs of lugs 43 or immediately beyond the foremost and rearmost of these lugs. Pairs of lugs 52, 53 are disposed along both upper and lower portions of the base plate 51 and

each such lug is provided with a groove 54. Whether employed for left-hand or right-hand feed, the grooves of the lowermost lugs receive the pin 44 to retain the guide structure 50 in position at that end of the feedway 13 toward which the ammunition moves. As shown in full lines in Fig. 4, the guide structure 50 is adapted for left-hand feed. When employed for right-hand feed, it is merely upturned and inserted as indicated by dotted lines 56. In either instance, the cover 12, when closed, aids in retaining the guide structure 50 in proper position.

Fixed rigidly to the base plate 51 is a rear cartridge stop 58 and a front cartridge stop 59, respectively engaged by the case and bullet of the cartridge when in extraction position. In addition, a link stripper 60 is also rigidly connected to the base plate and can serve as a cartridge stop. Its innermost end has a semi-circular channel conforming in shape with the periphery of the case. The lip of the link stripper immediately around this semi-circular channel engages the rear side 21 of the loop 19, which frictionally engages the cartridge case, all in such manner as to retain the link from rearward motion when the cartridge is extracted. Preferably, the cartridge stops 58, 59 and the link stripper 60 are integral with the base plate 51. If desired, a web 62 may extend between and further rigidify the cartridge stop 58 and the link stripper 60. The height of the cartridge stop 59 is such that the lower face thereof rests on the floor of the feedway 13 and the upper face thereof is contacted by the cover 12.

Also attached to, and preferably integral with, the base plate 51 is a guide member 65 in which reciprocates a gate or plunger 66 acting as a link-guide member. The guide member 65 may be integral with the front cartridge stop 59, as shown, or separate therefrom. It provides a guideway, shown as T-shaped in cross section in Fig. 6, comprising a guide passage 68 and a side passage 69 opening longitudinally thereon, both passages extending substantially parallel to the direction of ammunition advancement along the feedway 13.

At least a portion of the plunger 66 conforms in cross-sectional shape to the guideway to slide therein. As shown, the plunger 66 includes a body portion 70 sliding in the guide passage 68 and a side portion 71 extending from, and preferably slidably journaled in, the side passage 69. The side portion 71 extends beyond the guide member 65 and provides a link-contacting face 73 spaced from the link stripper 60 a distance slightly greater than the width of the links between front and rear faces 20 and 21 to provide, between the face 73 and the link stripper 60, a link-receiving passage 74 guiding the released links to a link-discharge opening 75 of the base plate 51. The forward portion of the link-contacting face 73 is curved or beveled to provide a curved portion 76 terminating in a cartridge-engaging end portion 77 at the innermost end of the plunger 66.

Means is provided for resiliently urging the plunger 66 inward, i. e., toward the advancing ammunition moving along the feedway 13. In the preferred construction, the plunger 66 is hollow from near its end portion 77 to its base to receive a light spring 80. The base of this spring seats against a plug 81 secured in position in the guide passage 68, as by a transverse pin 82. This plug preferably carries a rod 83 centering the spring 80 and of such length that its end

forms a stop means limiting the movement of the plunger 66 upon engagement with the end wall of its hollow portion. The stop means may limit the plunger movement to help determine the extraction position of the cartridge but, preferably, is positioned to permit a slight overtravel of the plunger beyond its position when its end portion 77 is in engagement with a cartridge in the extraction position, whereby the normal retracted position of the plunger is determined by such cartridge engagement.

The maximum advanced position of the plunger 66 under the action of the spring 80, is determined by a stop means, best shown in Figs. 6 and 7. 15 As therein shown, the base end of the plunger 66 carries a stop member 85 sliding in an auxiliary side passage 86 of the guideway. A pin 87 extends into the auxiliary side passage 86 through the wall carrying the front cartridge stop 59 and 20 into the path of travel of the plunger-carried stop member 85. The advanced position of the plunger, determined by the stop member 85, is suggested by dotted lines 88 of Fig. 1 and should be such that the cartridge-engaging end portion 77, and preferably the entire curved portion 76 25 of the link-contacting face 73, is disposed beyond the center line of the cartridge A in the extraction position. The advanced position may be such as to permit the plunger 66 to engage cartridge 30 B ready to move into the extraction position, but this is not necessary and the preferred arrangement is to stop the plunger before its end portion 77 engages cartridge B.

The base plate 51 removably carries a link-discharge chute 90, which may be of any desired form and which receives the released links discharging through the link-discharge opening 75 of the base plate. As shown in Figs. 1, 3, 4, and 5, this chute 90 provides channel-shaped end walls 91 spot welded to cover members 92 to provide a chute passage 93, preferably curved downward and inward as best shown in Fig. 4. A frame-like attachment member 94 is spot welded to the upper ends of the chute walls and provides 40 flanges 95 symmetrical with threaded openings of the base plate 51, which openings receive screws 96. When changing the guide structure 50 from left-hand to right-hand feed, the screws 96 are removed and the link-discharge chute 90 45 is re-attached to the now-inverted guide structure 50 in the dotted line position 97 of Fig. 4.

The operation of the invention is as follows. Under the action of the actuating pawl means 33, the leading cartridge is moved into its extraction position determined by contact between the front stop 59 and the bullet; also, by contact of the cartridge case with the rear stop 58 and the link stripper 60. When the cartridge is in its extraction position, the plunger 66 is in its 50 retracted position shown in Figs. 1 and 5. The extractor 36 then moves forward and cams upwardly over the rear end of the cartridge. Any tendency to force the cartridge forward is impeded by contact between the front face 20 of the leading and partially-released link and the link-contacting face 73 of the plunger. In this connection, it should be noted that the frusto-conical forward loop 18 of the link engaging this cartridge prevents forward movement of the cartridge with respect to this link. The loop 22 of the partially-released leading link slides along the cartridge case 25 a very small distance until it engages the loop 19. Thereafter, any forward pressure applied to the cartridge is transmitted 55 from the loop 22 to the loop 18 and thence to 60 65 70 75

the link-contacting face 73 of the plunger. This prevents the round from moving forward until the nose of the bullet engages the forward wall of the feedway 13, as often took place in prior practice. It insures that the camrelure 66 of the cartridge shall not be displaced forward beyond the reach of the extractor 38, thus eliminating malfunctioning of the gun because of short rounds in the ammunition belt.

As the extractor, now engaged with the camrelure 38, moves rearwardly, the first result is to move the cartridge and its connected links rearwardly until the rear face 21 of the loop 19 surrounding the cartridge contacts the link stripper 60. This moves the forward face 20 of the partially-released loop minutely from the link-contacting face 73 of the plunger. Further rearward movement of the extractor draws the cartridge from its associated loops 18, 19, and 22, freeing the leading link which is restrained from tipping in the link-receiving passage 74 by the close adjacency of the link-contacting face 73.

As the cartridge starts to move rearwardly from the link, the end portion 77 of the plunger 66 remains in resilient contact, first with the cartridge case 25 and later with the bullet 26, gradually moving forward as the taper of the bullet nears the curved portion 76. As soon as the tip of the bullet clears the plunger 66, this plunger is forced quickly inward to its advanced position. Because the front face 20 of the released link has been displaced rearwardly a slight distance from the link-contacting face 73, the plunger is unrestrained in its movement toward advanced position.

When the actuating pawl means 33 starts to advance the next round from position B toward the extraction position, this round engages the cartridge-engaging end portion 77 of the plunger to move the plunger into its retracted position.

In the meantime, however, it is important to notice that the plunger, when in its advanced position, disposes the link-contacting face 73 opposite the front face 20 of the loop 18 from which a cartridge has just been withdrawn, thus preventing the ammunition from moving forward in the feedway 13 and serving as a positive guide for the advancing ammunition through guidance of the links 17 interconnecting the rounds. Advancement of the new cartridge to the extraction position forces the previously-released link along the link-receiving passage 74, while still being guided and prevented from tipping by the link-contacting face 73. The released links are discharged through the link-discharge opening 75 and the chute passage 93.

The embodiment of the invention shown in Figs. 9 and 10 differs from that previously described in several respects. In the first place, the grooves 54 in the lugs 52, 53 are replaced by openings 100 adapted to receive the pin 44. In the second place, the plunger 66 and the guideway of the guide member 65 are formed of a different, though T-shaped, cross section. Here, the guide passage 68 and the body portion 70 of the plunger are circular in cross section rather than substantially square, as previously described.

Also, the embodiment of Figs. 9 and 10 differs in the mode of attachment of the chute 90 to the guide structure 50. In the modified embodiment, the frame-like attachment member 94' dovetails into a vertical channel 105 in the rear of the base plate 51, and the chute 90 is connected directly thereto to be removable therewith. Each edge of the attachment member 94' provides a notch

106 which lies opposite a spring-operated latch 107 when the attachment member aligns the chute 90 with the link-discharge opening 75 of the base plate. This construction provides for quick detachment of the chute 90 merely by moving a lever 108 to withdraw the latch 107 from its notch 106, whereupon the attachment member 94' and its connected chute may be lifted from the channel 105. For right-hand feed, the guide structure 50 is upturned and re-inserted in the left-hand end of the feedway. The attachment member 94' is removed from its channel 105 and reversed to bring the notch 106 on the opposite side into operative relationship with the latch 107.

In the embodiment of Fig. 11, the link-contacting face corresponding to that previously indicated by the numeral 73 is indicated by the numeral 119 and is provided by a link-contacting member 120 welded or otherwise secured to the side portion 71. This member 120 is plate-like in form to present a more extensive link-contacting face, a feature particularly desirable when a different form of link is employed in which the leading portions of the loops 18 and 19 are split, the member 120 preventing any possibility of the smaller side portion 71 entering and expanding the split portion. It should be clear, however, that the member 120 is equally useful for the link construction illustrated.

The member 120 preferably provides a main portion 121 of a height slightly greater than the height of the front stop 59 or the guide member 65, and a tapered portion 122 which is bent to follow the curved portion 76. Further, the member 120 preferably provides an end portion 123 overlying the previously described end portion 77 of the plunger. In this embodiment, the faces of the guide member 65 on opposite sides of its side passage 69 are cut back as indicated at 125 to provide adequate clearance for the movement of the main portion 121 of the member 120. As before, the link-contacting face 119 is spaced from the link stripper 60 a distance slightly greater than the width of the links between front and rear faces 20 and 21 to provide the link-receiving passage which guides the released links toward the chute 90. The wider link-contacting face 119 of this alternative form aids additionally in preventing undesirable tipping or misalignment of the released links as they move toward the chute 90.

Various changes and modifications can be made without departing from the spirit of the invention as defined in the appended claims.

I claim as my invention:

1. In an automatic gun having a transverse feedway and means for advancing a cartridge therealong to an extraction position, the combination of: stop means engaging said cartridge to limit its movement and dispose it in said extraction position; a plunger extending in said feedway in the path of movement of said cartridge; and means for resiliently urging said plunger into contact with the advancing cartridge before its engagement with said stop means.

2. In an automatic gun having a transverse feedway and means for advancing link-connected cartridges therealong, the combination of: stop means engageable with the leading cartridge to stop same in an extraction position; a plunger movable to and fro in the general direction of movement of said cartridges along said feedway and disposed in the path of movement thereof to engage the leading cartridge before this car-

tridge reaches said extraction position; and a light spring resiliently urging said plunger toward said leading cartridge.

3. A combination as defined in claim 2, in which said stop means includes a link stripper disposed to contact a cartridge in said extraction position on one side of its connected link, and in which said plunger is spaced from said link stripper to engage said cartridge on the opposite side of said link.

4. A combination as defined in claim 2, in which said stop means includes a link stripper disposed to contact a cartridge in said extraction position on one side of its connected link, and in which said plunger is spaced from said link stripper to engage said cartridge on the opposite side of said link, said plunger providing a link-contacting face spaced from said link stripper a distance only slightly greater than the width of said link measured longitudinally of said cartridge to form a link-guiding passage.

5. In an ammunition guide means for an automatic gun having a transverse feedway, having means for advancing link-connected cartridges therealong to dispose the leading cartridge in an extraction position, and having an extractor for extracting this cartridge from its associated links when this cartridge is in said extraction position, said ammunition guide means comprising: a plunger disposed to be in engagement with said leading cartridge when in said extraction position; and means for quickly extending said plunger in a direction substantially counter to the direction of advancement of said link-connected cartridges as soon as said extractor withdraws said leading cartridge from its connecting links.

6. An ammunition guide means as defined in claim 5, in which said last-named means includes a spring urging said plunger into resilient engagement with said leading cartridge until withdrawn by said extractor, said spring then advancing said plunger toward the next cartridge, said plunger moving at least to the center line of a cartridge when disposed in said extraction position.

7. An ammunition guide means as defined in claim 5, in which said plunger is disposed to extend in front of an unreleased link on a cartridge in said extraction position, and in which said plunger provides a face immediately forward of such link to resist forward motion of the link and cartridge axially of said gun and thus maintain the rear of said cartridge in proper position for engagement by said extractor.

8. An ammunition guide means for an automatic gun adapted to advance an ammunition belt comprising link-connected cartridges along a transverse feedway to dispose the leading cartridge in an extraction position, said ammunition guide means including: a guide member positioned beyond said extraction position and providing a guideway extending toward the advancing cartridges; a plunger having a cartridge-engaging portion, said plunger being inwardly movable along said guideway from a retracted position in which said cartridge-engaging portion contacts a cartridge in said extraction position to an advanced position in which said portion extends beyond the center line of a cartridge when in said extraction position to contact a cartridge moving toward said extraction position; stop means for limiting the inward movement of said plunger when in said advanced position; and a spring urging said plunger from

said retracted position toward said advanced position.

9. An ammunition guide means for an automatic gun adapted to advance an ammunition belt comprising link-connected cartridges along a transverse feedway to dispose the leading cartridge in an extraction position, said ammunition guide means including: a guide member positioned beyond said extraction position and providing a guideway extending toward the advancing cartridges; a plunger slidable in said guideway and having a cartridge-engaging end portion and a link-contacting face to one side of said guideway, said link-contacting face being movable adjacent the forward faces of the links of said ammunition belt; and means for resiliently urging said plunger inwardly to dispose said end portion in the path of a cartridge advancing to said extraction position to be contacted thereby, said end portion remaining in contact with such cartridge until it reaches said extraction position and until it is subsequently extracted from its connected links, said resilient means then moving said plunger again inward to move said link-contacting face adjacent the link being released by extraction of its associated cartridge to retain this released link in alignment with the other links of said ammunition belt.

10. An ammunition guide means for an automatic gun adapted to advance an ammunition belt comprising link-connected cartridges along a transverse feedway to dispose the leading cartridge in an extraction position, said ammunition guide means including: a guide member positioned beyond said extraction position and providing a guide passage extending toward the advancing cartridges and a side passage opening on said guide passage; a plunger providing a body portion slidable in said guide passage and providing a side portion extending from said side passage, said side portion providing a link-contacting face movable adjacent the links of said ammunition belt, said body portion providing a cartridge-engaging end portion; and means for resiliently urging said plunger inwardly to dispose said end portion in the path of a cartridge advancing to said extraction position to be contacted thereby, said end portion remaining in contact with such cartridge until it reaches said extraction position and until it is subsequently extracted from its connected links, said resilient means then moving said plunger again inward to move said link-contacting face adjacent the link being released by extraction of its associated cartridge to retain this released link in alignment with the other links of said ammunition belt.

11. An ammunition guide means as defined in claim 10, in which said plunger is hollow, and in which said resilient means comprises a spring disposed in the hollow plunger.

12. A guide structure for an automatic gun in which link-connected cartridges are advanced along a transverse feedway to dispose the leading cartridge in an extraction position, said guide structure including: a base plate; connection means for removably connecting said base plate to said gun at the end of said transverse feedway toward which said cartridges move; a link stripper rigidly secured to said base plate; a guide member rigidly secured to said base plate; a plunger movable relative to said guide member; and means for resiliently urging said plunger toward the leading cartridge advancing toward

said extraction position, said link stripper and said plunger being spaced to define a link-receiving passage guiding the links as they are released upon extraction of the cartridges.

13. A guide structure as defined in claim 12, in which said base plate provides a link-discharge opening communicating with said link-receiving passage.

14. A guide structure as defined in claim 12, in which said base plate provides a link-discharge opening communicating with said link-receiving passage, and including a link-discharge chute carried by said base plate for receiving the released links.

15. A guide structure as defined in claim 12, including a link-discharge chute for receiving the released links, and means for detachably connecting said link-discharge chute to said base plate, and in which said connection means includes means for detachably connecting said guide structure to said gun for selective right-hand and left-hand feed of said cartridges thereto, said means for detachably connecting said link-discharge chute to said base plate being reversible to accommodate the discharge of said links when said guide structure is disposed for either right-hand or left-hand feed.

16. A guide structure as defined in claim 12, including a stop means for limiting the motion of said plunger toward the leading cartridge advancing to said extraction position to limit the advancing movement of said plunger to a position in which at least a portion of said plunger traverses the center line of a cartridge when disposed in said extraction position.

17. A guide structure for an automatic gun in which link-connected cartridges are advanced along a transverse feedway to dispose the leading cartridge in an extraction position, said guide structure including: a base plate removably connectable to said gun at the end of said transverse feedway toward which said cartridges move; and means carried by said base plate for forming a link-receiving passage, said means including walls carried by said base plate in spaced relationship to bound said link-receiving passage, said walls extending along said feedway toward said extraction position, one of said walls providing a curved face to provide a link-receiving passage which flares in width toward said extraction position.

18. A unitary guide structure for attachment to an automatic gun for selective right-hand and left-hand feed of link-connected cartridges to and along a transverse feedway of said gun to dispose the leading cartridge in a predetermined extraction position, said gun including bracket means

on opposite sides thereof adjacent the ends of said transverse feedway, said unitary guide structure including: a base plate providing a link-discharge opening; a first member carried by said base plate and of a height to fit in either end of said feedway, said first member being positioned by said base plate and providing an inner end engageable with the leading cartridge to determine said extraction position; a second member carried by said base plate and of a height to fit in either end of said feedway, said second member being positioned by said base plate to extend in said feedway in spaced relationship with said first member to define a link-receiving passage therebetween, said link-receiving passage extending to said link-discharge opening of said base plate to guide the released links in their movement to said opening, said members providing link-guiding walls facing each other and bounding said link-receiving passage; attachment means at the bottom of said base plate for removable connection to said bracket means on one side of said gun to mount said guide structure on the gun in a first position with said first and second members of the guide structure extending in said feedway from one end thereof; and attachment means at the top of said base plate for removable connection to said bracket means on the other side of said gun when said guide structure is in inverted position to mount said guide structure on the gun with said first and second members extending in said feedway from the other end thereof.

19. A unitary guide structure as defined in claim 18 including also at least one cartridge stop rigidly secured to said base plate and spaced from said first and second members to extend in said feedway and providing an end surface engaged by the leading cartridge to determine its extraction position.

EDWARD CYRIL HOLTON.
